RESONANT DIRECTIONAL COUPLERS FOR MILLIMETRIC WAVE LENGTHS

Pierre G. Marié, Paris, France

Application July 18, 1956, Serial No. 598,561

9 Claims. (Cl. 333—10)

The present invention relates to resonant direction couplers particularly adapted for use with electromagnetic waves having a wave length of the order of magnitude of millimeters. Such couplers are employed for example to couple a rectangular wave guide (connected for example to a transmitter or receiver) to a circular wave guide in which an electromagnetic wave is to be propagated over large distances in the TE_{01} mode.

In applicant's copending application filed June 15, 1956, and entitled Wide Band Resonant Directional Couplers, there are described directional couplers for joining a rectangular guide to a circular guide in which the waves are to be propagated in the TE_{11} mode. These couplers, which are appropriate where the circular wave guide is to be short, are not suitable when the circular guide is to have a long length. In circular guides the TE_{01} mode is preferable since it has lower attenuation than the other modes, and an attenuation which decreases with frequency.

According to one feature of the directional coupler of the invention, the rectangular guide issuing from the energy source, whether a transmitter or receiver, and the circular guide to which it is to be coupled have their axes parallel along the distance used for coupling purposes. Moreover the two are joined by two resonators of identical dimensions constituted by rectangular guides closed upon themselves. Each of these resonators includes two straight portions and two semicircular portions. These resonators will hereinafter be called "annular guides." The straight portions of each resonator are directionally coupled, one to the rectangular guide and the other to the circular guide. With respect to the lengthwise axes of the rectangular and circular guides, which are parallel, the two resonators are displaced with respect to each other by a quarter of a guide wave length therein in order to conform to the phase conditions relating to the different modes of wave.

The invention will now be further described in conjunction with the accompanying drawings in which:

Fig. 1 is a cross sectional view of a coupler according to the invention, the section being taken on a plane 1—1 of Fig. 2 perpendicular to the parallel axes of the rectangular and circular guides which the coupler is to join;

Fig. 2 is a fragmentary sectional view of the coupler of Fig. 1 taken on the line 2—2 of Fig. 1;

Fig. 3 is a fragmentary sectional view of the coupler of Fig. 1 taken on the line 3—3 of Fig. 1;

Fig. 4 is a schematic diagram illustrating in the coupler of Fig. 1 the relationship of the resonators with respect to the rectangular and circular guides which they couple together;

Fig. 5 is a diagrammatic representation of a directional coupler according to the invention including a plurality of pairs of annular resonators connected in parallel;

Fig. 6 is a diagram of a further arrangement of couplers according to the invention all employing a common circular guide, the whole forming a multichannel filter; and

2

Fig. 7 is a diagram of a tuning device for annular resonators.

The example of the coupler of the invention to be described is made up exclusively of machined elements 5 suitably fastened together as for example by screws. While this form of construction is advantageous in order to achieve the dimensional accuracy necessary for operation in the range of millimetric wave lengths, the invention is not limited thereto.

10 Apart from the tuning elements, the directional coupler of Figs. 1—3 comprises five principal parts 1—5 identified in Fig. 1. These parts define and enclose openings or cavities, which form the circular guide section 6, the rectangular guide section 7 and the annular guides 8 and 9. The four guides have dimensions such that they have the same guide wave length.

15 Between the two members 1 and 2 there is formed a cylindrical opening 6 which constitutes the circular guide and in which the waves are propagated in the TE_{01} mode employed for transmission over long distances.

20 Adjacent the entering and emergent ends of the coupler, shown in Fig. 2 at 15 and 16 for the circular guide 6, the members 1 and 2 possess mating plane faces 10 and 10' which lie in contact with each other, stressed together by screws 11 and members 4 and 5 which hold members 1 and 2 together. In Fig. 2 the members 1 and 2 are shown slightly spaced apart. Over part of the 25 length of the plane faces 10 there are provided depressions 12 which, when the members 1 and 2 are assembled together, define the slots 13 and 14 shown in Fig. 1.

25 The ends of the cylindrical opening 6 are threaded at 15 and 16 for accommodation of the ends of the circular guide in which the energy is to be transmitted over long distances in the TE_{01} mode.

30 Between the members 1 and 3 there is provided a rectangular opening 7, the walls of which constitute a rectangular guide section connecting with the rectangular guide 17 coupled to the associated apparatus, transmitting or receiving for example. In practice it is convenient actually to extend this external guide 17 into and solder or weld it to the member 3, as indicated in Figs. 1 and 3, the bottom wall of the guide 17 being cut away over the central portion of the coupler as indicated at 35 19.

35 The members 1 and 3 contact each other only along mating plane surfaces 18 and 18' on opposite sides of the central portion of the coupler, i.e. on opposite sides of the portion over which extend the slots 13 and 14. In the central portion of the coupler the adjacent faces 19 and 19' of members 1 and 3 are spaced apart to define slots 23 and 24 as indicated in Fig. 1. These slots extend over the length of guide 17 from which the bottom wall is removed and, preferably over the same length as slots 40 13 and 14.

45 The members 1 and 3 contact each other only along mating plane surfaces 18 and 18' on opposite sides of the central portion of the coupler, i.e. on opposite sides of the portion over which extend the slots 13 and 14. In the central portion of the coupler the adjacent faces 19 and 19' of members 1 and 3 are spaced apart to define slots 23 and 24 as indicated in Fig. 1. These slots extend over the length of guide 17 from which the bottom wall is removed and, preferably over the same length as slots 40 13 and 14.

50 The slots 13, 23 and 14, 24 have lengths equal to several wave lengths and operate to effect directional coupling of the rectangular and circular guides 6 and 7 to the annular guides 8 and 9. These annular resonators are formed one in members 1, 2, 3 and 4 and the other in members 1, 2, 3, and 5. For the resonator 8, member 4 includes a channel of rectangular cross section having a depth equal to half the wide dimension of the rectangular guide which, being closed on itself, forms the resonator 8. This loop-shaped channel has a shape which, as seen in Fig. 4, 55 comprises two parallel straight portions joined by two semi-circular portions. The other half of the resonator 8 is of matching shape and is formed by suitable conformation of members 1, 2 and 3 near the faces thereof which

60 join with member 4, as indicated in Fig. 1. The construction is such that when members 1, 2, 3 and 4 are assembled together with screws 11, slot 23 communicates with 65 70

the upper straight portion of resonator 8 while slot 13 communicates with the lower straight portion thereof.

The resonator 9 is similarly formed in members 1, 2, 3 and 5, but displaced lengthwise of the coupler, i. e. of the parallel axes of guides 6 and 7, by a quarter of a wave length as indicated in Fig. 4. Fig. 4 shows the projection, onto the plane identified by the section lines 2-2 and 3-3 in Fig. 1, of the mid-sections of the annular guides 8 and 9. For guide 8 this mid-section appears at the interface between member 4 and members 1, 2 and 3. For guide 9, the mid-section appears at the interface between member 5 and members 1, 2 and 3. In Fig. 4 the projection for guide 9 is shown in full lines at 21 while the projection for guide 8 is shown in dashed lines at 26, except that lines 21 and 26 coincide in their straight portions. The slots 13 and 14, which have the same projections on the plane of Fig. 4, are shown together, and similarly in the case of slots 23 and 24. Fig. 4 further shows in light dashed lines the generatrices which constitute the limits of guides 6 and 7.

As indicated in Fig. 4 the two resonators 8 and 9 are displaced by a quarter of a wave length. M_0 , M'_0 , M_1 , M'_1 , M_2 and M'_2 indicate in Fig. 4 the cross sectional locations of the guides at which the complex intensities of the waves are measured. According to a theory developed in detail in applicant's publication entitled "Theorie et Applications des Biquadriondes" a wave of intensity t_0 crossing the section plane M_0 in guide 7 is divided into two parts. One part is further propagated down the rectangular guide 7, arriving at the section plane M'_0 with an intensity r_0 . The other part penetrates through the slots 23 and 24 into the upper rectilinear portions of the resonators 8 and 9, the slots 23 and 24 acting as directional couplers. This latter part of the energy is then further propagated across the plane M_1 at the section planes 29 and 30 (Fig. 4). The waves which arrive at sections 29 and 30 are in quadrature since they were excited in phase through the slots 23 and 24 and since the two resonators 8 and 9 are displaced, lengthwise of the parallel axes of guides 6 and 7, by a quarter of a guide wave length, $\lambda_g/4$. Let t_1 be the total intensity across the plane M_1 at the sections 29 and 30. t_1 is a complex number whose modulus is the square root of the total flux of energy crossing the sections 29 and 30, its argument being the average of the phases at these sections.

The waves which have traversed the sections 29 and 30 continue and arrive at the slots 13 and 14 in phase opposition as is desirable for excitation of the TE_{01} mode in the circular guide 6. The slots 13 and 14 act as directional couplers, and the energy which arrives from the sections 29 and 30 is shared between the TE_{01} wave excited in the circular guide 6 and the waves which continue within the guides 8 and 9, arriving at the plane M'_1 of the sections 31 and 32 with an intensity r_1 .

The intensity r_1 is expressed as a complex number whose modulus is equal to the square root of the total flux of energy crossing the sections 31 and 32, its argument being the average of the phases at these sections.

Let t_2 be the intensity of the wave thus propagated across the section 33 at the plane M_2 in the circular guide 6, this intensity being defined in terms of the square root of the flux of energy of that wave.

If in the circular guide there is introduced across the section 34 at the plane M'_2 a wave of intensity r_2 , its energy will reinforce the waves of intensity t_2 and r_2 .

In applicant's publication already cited applicant has shown that the matrix relation

$$\begin{vmatrix} t_0 \\ r_0 \end{vmatrix} = \begin{vmatrix} T \end{vmatrix} \times \begin{vmatrix} t_1 \\ r_1 \end{vmatrix}$$

which relates the intensities t_1 , r_1 , t_2 , r_2 is the same as that which relates the total incident transmitted and re-

flected intensities of optical waves which exchange energy across a partial reflecting plane having no losses.

Similarly the energy corresponding to a total intensity r_1 for the waves which cross the sections 31 and 32 reinforces the waves of intensity r_0 and t_1 . Between the total intensities t_0 , r_0 , t_1 , r_1 there exists a matrix relation as follows analogous to that previously given:

$$\begin{vmatrix} t_0 \\ r_0 \end{vmatrix} = \begin{vmatrix} T \end{vmatrix} \times \begin{vmatrix} t_1 \\ r_1 \end{vmatrix}$$

When one disposes in parallel two partially reflecting planes to form a Perot-Fabry interferometer, the waves whose frequency corresponds to the resonant frequency of the resonator included between the two planes pass through the interferometer whereas the others are reflected. Similarly, in the case of the resonant directional coupler of the present invention, if the energy enters in the form of a wave of intensity t_0 , the totality of the energy will reappear in the wave of intensity t_2 , provided the frequency is close to a frequency of resonance for the resonators 8 and 9. The energy is further propagated in the form of a wave of intensity r_0 if the frequency differs too widely from the resonant frequencies of resonators 8 and 9. The different resonant frequencies of the resonators can be computed by noting that the average length of the annular guide closed on itself must for such resonance be equal to an integral number of wave lengths.

In applicant's copending application above identified it is shown that a number of directional resonant couplers can be connected in parallel between the guides in order to obtain an improved filtering effect. Similarly in the case of the present invention, as schematically indicated in Fig. 5, two pairs of annular resonators 35-36 and 37-38 couple a rectangular guide 7 to a circular guide 6. The two resonators 35 and 36 are tuned to the same frequency and are displaced by $\lambda_g/4$ while the two resonators 37 and 38 are tuned to a different frequency. In this manner it is possible to pass very wide bands of frequency, by interspersing the resonant frequencies $f_1, f_2, \dots, f_n$ of the first pair of resonators 35-36 with the resonant frequencies $f'_1, f'_2, \dots, f'_n$ of the second pair of resonators 37-38 and by providing that the widths of the pass bands for the successive resonances shall be equal to the spacing of adjacent resonances.

Fig. 6 illustrates schematically three directional couplers 39, 40 and 41 coupled on one side to a common circular guide 42 and on the other side to separate rectangular guides 57, 58 and 59. The pairs of resonators 43-44 of the coupler 39, 45-46 of the coupler 40, and 47-48 of the coupler 41 are respectively tuned to 35,100 and 35,200 and 35,300 megacycles and have pass bands of approximately 40 megacycles each. At the end 49 of the guide 42 there enter waves whose frequencies are above 35,000 megacycles. The receivers 50 and 51 are intended to cover the bands 35,080 to 35,120 and 35,180 to 35,220 mc. respectively.

The transmitter 52 radiates waves within the band 35,280 to 35,320 mcs. toward the end 49. Thus there are connected to a common circular guide 42 a number of transmitters and receivers which divide between them a band of wave lengths several thousand megacycles in frequency wide, all of which the circular guide is able to transmit. 53 to 56 indicate suitable dissipative terminations.

In the foregoing it has been assumed that the resonators were tuned in their initial dimensioning. In practice it is necessary to provide for adjustment of such tuning. Fig. 7 shows an arrangement suitable for this purpose. In this figure there is shown at 60 a section of one of the resonators, taken on the plane which includes the median section of the wide sides of the guide. 61 is a metallic or dielectric blade insertable and retractable by means of the screw 62 having a knurled button 63 on the end of it.

Whereas the invention has been described in terms of preferred embodiments various changes may be made therein. For example while the coupling elements have been described as slots, they may of course take the form of pluralities of aligned apertures.

I claim:

1. A resonant mode-selective directional coupler comprising a rectangular wave guide section, a circular wave guide section parallel thereto and dimensioned to the same cut-off frequency in the TE_{01} mode as said rectangular section, two resonant loop-shaped rectangular wave guides having the same cross section, said loop-shaped guides being dimensioned to the same cut-off frequency as said rectangular and circular sections, and means directionally coupling each of said loop-shaped guides to both of said guide sections, said loop-shaped guides being displaced one with respect to another lengthwise of said rectangular and circular guide sections by substantially a quarter of a guide wave length within said loop-shaped guides.

2. A resonant mode-selective directional coupler for radiation of millimetric wave lengths comprising an input rectangular wave guide section, an output circular wave guide section supported parallel to said rectangular wave guide section and dimensioned to the same cut-off frequency in the TE_{01} mode as said rectangular section, and two substantially identical cavity resonators each directionally coupled to both of said wave guide sections, said resonators having the shape of loop-shaped rectangular wave guides closed on themselves, said resonators being dimensioned to the same cut-off frequency as said rectangular and circular sections, said cavity resonators being displaced with respect to each other lengthwise of said guide sections by substantially a quarter of a guide wave length in said loop-shaped rectangular guides, said resonators being further coupled to said guide sections at the same positions lengthwise of said guide sections.

3. A resonant mode-selective directional coupler comprising a rectangular wave guide section, a circular wave guide section parallel thereto dimensioned to the same cut-off frequency in the TE_{01} mode as said rectangular section, two resonant loop-shaped rectangular wave guides, and means directionally coupling each of said loop-shaped guides to said guide sections, said loop-shaped guides having the same dimensions and being dimensioned to the same cut-off frequency as said rectangular and circular sections and being separated lengthwise of the axes of said guide sections by substantially a quarter of a guide wave length in said loop-shaped rectangular guides, the loop length of each of said loop-shaped guides being substantially an integral number of said guide wave length.

4. A resonant mode-selective directional coupler comprising a rectangular wave guide section, a circular wave guide section parallel thereto dimensioned to the same cut-off frequency in the TE_{01} mode as said rectangular section, two resonant loop-shaped rectangular wave guides, and means directionally coupling each of said loop-shaped guides to said guide sections, said loop-shaped guides having the same dimensions and being dimensioned to the same cut-off frequency as said rectangular and circular sections and being separated lengthwise of the axes of said parallel guide sections by substantially an odd multiple of a quarter of a guide wave length for radiation travelling in said loop-shaped guides in the TE_{10} mode, the loop length of each of said loop-shaped guides being substantially an integral number of said guide wave length.

5. A resonant mode-selective directional coupler adapted to interconnect rectangular and circular wave guides, said coupler comprising sections of rectangular and circular wave guides having their axes parallel to each other, said guide sections being dimensioned to the same cut-off frequency in the TE_{01} mode as said rec-

tangular section two rectangular wave guides of the same dimensions closed upon themselves into loop shape to form two resonant cavities, said loop-shaped guides being dimensioned to the same cut-off frequency as said rec-

tangular and circular guide sections, each of said closed guides including two straight portions joined together by curved portions, means directionally coupling one straight portion of each of said closed guides to said rectangular guide section, and means directionally coupling the other straight portion of each of said closed guides to said circular guide section, said closed guides being positionally staggered lengthwise of said axes, by substantially an integral multiple of a quarter of a guide wave length for a wave in said closed guides.

6. A resonant mode-selective directional coupler comprising rectangular and circular wave guide sections supported parallel to each other with their axes defining a plane substantially perpendicular to the wide dimension of the rectangular guide section, said sections being dimensioned to the same cut-off frequency in the TE_{01} mode as said rectangular section, two resonant closed loop rectangular guides of the same dimensions supported on opposite sides of said plane, said closed guides being dimensioned to the same cut-off frequency as said

rectangular and circular guide sections said closed guides being positionally staggered lengthwise of the parallel axes of said guide sections by a quarter of a guide wave length for a wave in said closed guides, said closed guides having a length amounting substantially to an integral multiple of said guide wave length and including each two straight portions parallel to said axes joined by two semicircular portions, and means directionally coupling the straight portions of each of said closed guides one to said rectangular guide section and the other to said circular guide section, said directional coupling means being substantially equally spaced lengthwise of said axes.

7. A resonant mode-selective directional coupler comprising rectangular and circular wave guide sections supported parallel to each other with their axes defining a plane substantially perpendicular to the wide dimension of the rectangular guide section, said circular guide section being dimensioned to the same cut-off frequency in the TE_{01} mode as said rectangular guide section, two resonant closed loop rectangular guides of the same dimensions, said closed guides having the same cross sectional dimensions as said rectangular guide section and being supported on opposite sides of said plane at equal distances therefrom, said closed guides being positionally staggered lengthwise of the parallel axes of said guide sections by a quarter of a guide wave length for a wave in said rectangular guide section, said closed guides having a length amounting substantially to an integral multiple of said guide wave length and including each two straight

portions parallel to said axes joined by two semicircular portions, and means directionally coupling the straight portions of each of said closed guides one to said rectangular guide section and the other to said circular guide section, said directional coupling means being substantially equally spaced lengthwise of said axes and extending over a plurality of said guide wave lengths.

8. A resonant mode-selective directional coupler adapted to connect a rectangular wave guide to a circular wave guide for the propagation of energy in said circular wave guide in the TE_{01} mode, said coupler comprising a rectangular wave guide section, a circular wave guide section supported parallel to said rectangular guide section, said circular guide section being dimensioned to the same cut-off frequency in the TE_{01} mode as said rectangular guide section, two resonant closed loop rectangular wave guides of the same dimensions, said closed guides being dimensioned to the same cut-off frequency as said rectangular and circular guide sections said closed guides being positionally staggered lengthwise of the parallel axes of said guide sections by a quarter of a

guide wave length for a wave in said closed guides, said closed guides having a length amounting substantially to an integral multiple of said guide wave length and including each two straight portions parallel to said axes joined by two semicircular portions, and means directionally coupling the straight portions of each of said closed guides one to said rectangular guide section and the other to said circular guide section, said directional coupling means being substantially equally spaced lengthwise of said axes.

9. A resonant mode-selective directional coupler adapted to interconnect a rectangular input wave guide and an output circular wave guide for the propagation of energy in said circular wave guide in the TE_{01} mode, said coupler comprising a rectangular wave guide section 15 adapted to support a wave in the TE_{10} mode, a circular wave guide section supported parallel to said rectangular guide section, said circular guide section being dimensioned to the same cut-off frequency in the TE_{01} mode as said rectangular guide section, two resonant closed loop 20 rectangular wave guides of the same dimensions, said closed loop guides being dimensioned to the same cut-off

frequency as said rectangular and circular guide sections, said closed guides being positionally staggered lengthwise of the parallel axes of said guide sections by a quarter of a guide wave length for a wave in said closed guides, said

5 closed guides having a length amounting substantially to an integral multiple of said guide wave length and including each two straight portions parallel to said axes joined by two semicircular portions, and means directionally coupling the straight portions of each of said closed guides 10 one to said rectangular guide section and the other to said circular guide section, said directional coupling means being substantially equally spaced lengthwise of said axes.
